MACHINE FOR BURNING EDGES OF
LEATHER PIECESAlessandro Tosi and Roberto Tosi,
Busto Arsizio, ItalyApplication February 21, 1948, Serial No. 10,068
In Italy November 24, 1945Section 1, Public Law 690, August 8, 1946
Patent expires November 24, 1965

2 Claims. (Cl. 69—7.5)

1

The invention concerns machines for the finishing of edges of uppers used in shoe manufacture, by means of burning with a hot tool. With these machines, the leather stock to be worked comes in contact with the hot tool and burner that is at standstill, and is advanced by jumps. Particularly in the case of thin and flappy leather, this causes formation of wrinkles.

According to the present invention, in combination with means for intermittent advancing of the work piece, and in the intervals between said advancement steps, a burning tool that lowers until touching the edge of the leather piece and subsequently is lifted in such a manner that if the piece continues advancing, it is free from any contact with the hot tool.

Consequently, during the feed movement, the hide can be easily handled. Moreover, the burnt edge, not being any longer in contact with the tool, is free to follow the natural movement of curvature due to heating and, therefore, this effect is attained without needing application of the hammers as provided to this purpose in the known machine.

Furthermore, the fact that the burning tool is not in contact with the work piece but at the time at which it is operative, whence in the subsequent time interval, in which it is not operative, transfer of heat being due to contact, it has time to recover heat without needing recourse to the contrivances usual with the conventional machines, and causing inconstancy of working temperature and, therefore, a work not free from defects and overheating of the tool as with overall duration of same.

These and other features of the invention, together with some constructional particulars and combinations of parts will be described and illustrated in an example of a machine, and will be defined in the appended claims.

With reference to the accompanying drawing:

Fig. 1 is a front elevation of a machine embodying the present invention.

Fig. 2 is a view of a particular of the machine, showing a leather piece that is in the burning stage therewith.

Fig. 3 is a view of the same particular showing a leather piece that is in the stage immediately subsequent to the burning stage therewith.

On the work bench 1 there is fixed an arm 2, below said plane there is rotatably supported a transmission shaft 3 onto which there is fitted a drive flywheel-pulley 36.

On the shaft 3 there is fixed an eccentric 4, on which there is slidably a collar 5 provided with

5 a fork 6, with which the end of a rod 7 is articulated. The rod 7 is provided at its other end with a head 8 wherein there is housed in a mutually rotatable manner a pin 9, the axis of which is parallel to the axis of the shaft 3 and the ends of which are rigidly connected with the carriage 10 slidable on four small columns 11. Only two of these columns are visible, the other two being concealed therebehind. The uprights 11 are fixed on a support 12 apt to move in translation horizontally on the guide 13, with which the bench 1 is provided.

Said translation is obtained by way of the handle 16, on the rotation pin of which there is fitted an eccentric 17 cooperating with a channel 18 provided in the support 12. The carriage 10 presents a head 14, on which there is vertically slidable the slide 15, onto which a pin 19 is fastened.

20 The slide is provided with a vertical channel not visible in the drawing, with which engages the eccentric 20 fitted onto the small shaft 21 arranged rotatable and parallel to the pin 9 in the carriage 10 and controlled by means of the lug

25 22. On the slide 15 there is fixed and electrically insulated a plate 23 terminating the electric leads 24 carrying the current. The plate 23 carries the burning tool 25. Onto the end of shaft 3, a second eccentric 26 is fitted on which a collar 37 is rotatable and moving as a unit together with a toothed member 35.

Said collar is applied onto the table 1 by means of a double vertical and horizontal slide, whence it is apt to undergo vertical and horizontal displacements at the same time.

If the shaft 3 is in rotation, the member 35 undergoes in succession cyclically a lift, an advancement, a descension, a back displacement. This constitutes what is conveniently termed a walking beam type of feed member. Also in contact with the toothed surface a foot 27 is provided carried by the leg 28 slidable in the guide 29 provided in the arm 2, under the action of the spring 30.

40 45 In register with the toothed member 35, the table 2 presents a slot through which the said member 35 appears if it is in the lifted position. Below the members 19 and 25, a rest 31 is provided equipped with a stem 32 slidable in the vertical guide 33 rigidly connected to the table 2. Said rest 31 is elastically supple overcoming the elastic force of the spring 34 in cooperation with the pin 19 if the latter descends in such a manner as to take excessive stress away from the tool.

In operation, the work piece is gripped between

the toothed member 35 which is in the position indicated in Fig. 1, and the foot 27, in such a manner that its border projects above the supple rest 31 as can be seen in Fig. 1, and is dragged forward in the forward displacement of member 35. While the shaft 3 and the eccentrics 4 and 26 rotate, the member 35 lowers beneath the plane of the table as in Fig. 2, operating the advancement of the work piece. At the same time, the pin 19 has come to contact the rest 31 which has lowered and the edge of the piece of leather has assumed the position approximately of Fig. 2, in which also the heated tool 25 has come to contact the edge of the leather performing burning and the said leather edge while resting on the pin 19 tends to curve as shown in the figure by effect of heat.

By a subsequent rotation of the shaft 3, the member 35, still remaining below the level of the working plane, shifts backward, while the members 19 and 25 rise, followed to a certain extent by the rest 31 under the action of the spring 34. At this stage, the leather piece is placed and the pin 19 helps the edge of the leather piece to curve approximately as indicated in Fig. 3.

By further rotation of the shaft, the mutual position of the various parts is restored as indicated in Fig. 1.

By handling the handles 16 and 22 respectively, it is possible, in a known manner, to laterally adjust the position of the burning tool with respect to the edge of the work piece or to vary the distance of the members 19 and 25 from the rest plane 31.

Although the invention is described as embodied with a particular machine, it should be clearly understood that the invention is not limited in its application to the particular machine that has been illustrated and described.

We claim:

1. A machine for finishing the edges of uppers and other leather pieces as used in shoe manufacture comprising, in combination, a support surface on which the piece to be worked is made to advance, there being a slot in said support surface, a walking beam feed element moving in said slot alternately forward above and backward beneath said surface, a burning tool displaceable vertically on the edge of the piece to be worked, driving means for both said feed element and said tool acting so as to move said tool to contact said piece when said feed element is below said surface, and to move said tool away from said piece when said feed element is above said surface.

2. A machine according to claim 1, also including a pin, united firmly to said burning tool and positioned laterally with respect thereto, and toward the edge of the work piece, a resilient rest for the edge of the work piece, and means for causing said tool to make contact with said piece when said feed element is below said surface, and to remove said tool from said piece when said feed element is above said surface.
